UNITED STATES PATENT OFFICE

GALEN H. CLEVENGER, OF BROOKLINE, MASSACHUSETTS, ASSIGNOR TO UNITED STATES SMELTING, REFINING & MINING COMPANY, OF PORTLAND, MAINE, A CORPORATION OF MAINE

PIPE CLOSURE

Application filed July 23, 1929. Serial No. 380,310.

The present invention relates to pipe closures, and more particularly to a closure and the means for opening or clearing the same by the operator from a distant point by devices passed through the interior of the pipe.

The object of the present invention is to provide a device or apparatus of the character specified, which shall be simple in construction, inexpensive to manufacture, and quick and certain in operation. To the above ends the present invention consists in the devices and combinations of devices hereinafter described and claimed.

In the dredging for gold in Alaska and other northern countries, it has been found necessary in many localities to thaw the ground in order to enable the dredge to excavate the gold-bearing material. A common method of thawing has been by sinking pipes into the ground and forcing water through such pipes to thaw the surrounding ground. The United States patent to Miles, No. 1,339,036, dated May 4, 1920, discloses this method of thawing.

When these pipes are sunk during the warmer season the ground immediately in advance of the end of the pipe may be thawed by forcing water through the pipe. In the colder seasons, as spring and fall, when the temperature is so low that the thawing water cannot be used, it is the practice to drill a hole directly downward through the frozen ground and then setting an iron pipe in the hole, extending from above the surface of the ground to the very bottom.

Since this pipe must be open at its lower end to permit the escape of the thawing water when the thawing season comes, water is free to enter if the pipe is left open and may then freeze, bursting more or less of the length of pipe and interfering with its proper use with thawing water later in the season. Furthermore, since it is the practice to withdraw these pipes after the thawing is completed and use them again and again in other locations, considerable financial loss may result from such freezing, particularly since they are used so far from the source of supply where transportation costs are excessive.

The present invention is particularly

adapted for use with such thawing pipes in that it provides a water-tight closure for the lower end of the pipe which will effectually prevent the entrance of water into the pipe and later destructive freezing, yet is adapted to be opened or cleared by the operator quickly and with certainty from the upper end of the pipe by means passed through the interior of the pipe.

Briefly, the closure comprises a metal disk mounted or secured in the bottom end of the pipe to form an impervious partition, yet adapted to be torn away from its mounting and removed bodily from the upper end of the pipe. For this purpose the disk is provided with a hook engaging member adapted to be caught by a hook on the lower end of a rope or other means lowered into the pipe. By a lever device mounted upon the upper end of the pipe the operator is enabled to exert a heavy tension upon the rope and hook to tear away the partition from its mounting and thus open the lower end of the pipe.

In the accompanying drawings which illustrate a preferred construction of the present invention, Fig. 1 is a vertical sectional view showing the pipe closure in position in the end of the pipe with the co-operating devices in position for opening or clearing the pipe; Fig. 2 is a side elevation of the lever attachment on the upper end of the pipe, and Fig. 3 is a top plan of the same; Figs. 4 and 5 are elevations of adjacent faces or sides of the hook; Fig. 6 is a section on the line 6—6 Fig. 4; Fig. 7 is a section on the line 7—7, Fig. 5; Fig. 8 is a side view largely in section of the closure with its bail or loop; Fig. 9 is a transverse section on the line 9—9, Fig. 8; and Figs. 10 and 11 show the partition, the former in side elevation and the latter in axial end view before assembly.

In the construction shown in Figs. 1, 9 and 10, the closure comprises a mounting in the form of a hollow cylindrical sleeve 15 externally threaded for a portion of its length to engage the internal threads of a coupling 17 on the lower end of the pipe 19. Preferably the sleeve is provided with a series of radial openings 21 in the unthreaded projecting end portion in order to permit the

free lateral escape of the thawing water should the end of the closure be partially or completely sealed by a rock or otherwise.

Within the sleeve is the partition 23, which consists of a metal disk beveled at its edges as shown at 25 and secured to the sleeve by soldering at such edges, thus forming, when the sleeve is in position in the pipe, an impervious barrier sealing or closing the 10 end of the pipe.

Secured to this partition or disk is a wire 27, one end 29 of which is passed twice through the disk and then clenched against the face of the disk, while the other end is 15 formed into a bail or loop 31. Leakage around the wire where it passes through the disk is prevented by soldering.

Before the pipe is inserted in the ground the coupling 17 is screwed on to its lower end, 20 and then the closure is screwed into the coupling leaving the bail or loop standing upright in the pipe with the top of the bail or loop positioned substantially diametrically across the pipe. The pipe will now be lowered into the ground in the hole previously drilled, and may be left indefinitely without 25 possibility of any water entering the lower end of the pipe to freeze and cause damage.

The partition or disk is torn away from 30 the sleeve 15 by means of a rope lowered into the pipe and carrying at its end a hook for engaging the bail. This hook, shown separately in Figs. 4 to 7, comprises a head 33 of generally rectangular cross-section with bevelled corners as at 35. The lower end is pointed as at 37 to form a narrow, chisel-like extremity to guide and turn the head into proper position for the hook to catch the bail. The rear portion of the head is formed with 40 a longitudinal recess 39, within which is pivoted at 41 the double hook 43, with flaring prongs. Extending rearwardly from the head is the shank 45 carrying at its end the loop or eye 47 for attachment of the rope. 45 The springs 49 riveted to the shank 45 engage the inner faces of the prongs of the hook with yielding pressure to maintain the hook in proper alignment. These springs also serve to prevent the hook from being disengaged from the bail 31 on the partition or 50 disk when the bail has once entered the hook and passed the end of the spring. Fig. 1 shows this position of the parts. The rear end of the head is grooved and rounded as 55 at 50 to form seats for the bail.

In order to make it easier for the operator to exert sufficient pull upon the rope to tear away the partition or disk from the sleeve, a lever and mounting have been provided 60 adapted to be secured to the top of the pipe whereby a heavy strain or tension may be imparted to the rope. The lever and mounting are shown in Figs. 2 and 3, the lever being in the form of a wooden member having a long power arm 51 and a short work

arm 53 pivoted upon the horizontal stud 55. The work arm 53 is notched with the bottom of the notch rounded, as shown at 57, to receive the rope 59, and a fastening or cleat 61 is fixed upon the lever for fastening the rope. 70

The mounting of the lever comprises a sleeve 63 internally threaded so as to be screwed upon the upper end of the pipe 19. Extending from opposite sides of the sleeve are the two arms or ears 65, between the upper ends of which arms is pivoted the lever, while the lower ends of the arms carry the semi-circular foot 67 adapted to engage the wall of the pipe. The arms are stiffened by means of the studs 69 extending between the inner faces of the arms and welded or otherwise secured together. 75

In operation the closure is secured in the end of the pipe before the latter is lowered into the ground. When it is desired to open the pipe the hook and rope are lowered into the pipe until the lower end of the hook strikes the partition or disk. Owing to the shape of the point of the hook, the latter will be guided to one side or the other of the substantially diametrically located bail, the hook yielding slightly, if necessary, as it passes the top of the bail. The bail is of such length and proportions that when the head of the hook engages the disk or partition, the hook member will lie underneath the top of the bail in position to catch the latter when the rope and hook are drawn upward, the bail passing between one of the hooks and its contacting spring and engaging the rounded upper end of the head in one or the other of the grooves. The bail is now locked in the hook and secured against displacement even if the hook should again be lowered. 90

The operator continues to draw upon the rope until it is well tightened when he takes a bite about the cleat, the hand lever at this time having its handle raised and its rope engaging end lowered. The handle is next forced downwardly and through the greatly increased leverage exerts sufficient stress upon the rope to tear the partition away from the threaded sleeve and into the pipe. Since the diameter of the sleeve is slightly less than that of the pipe, ample clearance is afforded for the disk, once it is clear of the sleeve. Preferably the point of attachment of the bail is near one edge of the disk so that the separation of the disk from its mounting will start at one point and then progress around the disk. It is also of advantage to have the disk of sufficient thinness to permit more or less bending or distortion of the disk during the process. 100

After the disk has been freed from its sleeve, the operator can draw the rope easily by hand without the lever, and finally withdraw from the pipe the hook and disk. The hook may now be disengaged from the bail and the lever support removed from the upper 110

end of the pipe when the apparatus will be ready for use to clear or open another pipe.

While the present invention has been illustrated and described as embodied in a specific form and construction especially designed for a particular purpose and use, it is to be understood that the invention is not limited thereto but may be embodied in other forms and arrangements and applied to other uses.

Having thus described the invention, what is claimed is:

1. A pipe closure comprising a sleeve adapted to be secured in one end of a pipe, a partition secured in the sleeve, and a loop carried by the partition and extending into the pipe with its partition engaging end substantially diametrically across the pipe.

2. The combination with a disk adapted to be secured in one end of a pipe and having hook engaging means, of a hook member, said member carrying a hook pivoted thereon, and a spring engaging the inner face of the hook to permit yielding movement of the hook on its pivot and to lock the hook in engagement with said hook engaging means.

3. The combination with an impervious partition adapted to be secured in one end of a pipe and provided with hook engaging means, of a hook member comprising a head having a chisel-like extremity to guide the member, a double hook pivoted in the head, and springs normally closing the hooks to permit yielding movement of the hook and to close the hook to prevent disconnection from said hook engaging means.

4. A device for removing closures from pipes comprising a head having a chisel-like end and a longitudinal recess, a double hook pivotally mounted in the recess, a shank extending from the head and provided with means for attachment of a flexible member, and a pair of springs mounted on the shank and engaging the inner faces of the hooks.

5. A device for removing closures from pipes comprising a sleeve adapted to be mounted upon one end of the pipe, an arm extending from the sleeve, a lever pivoted upon the upper end of said arm with one end overlying the sleeve, cord fastening devices carried by the lever, and a curved abutment carried by the lower end of the arm and adapted to engage the pipe.

In testimony whereof I have signed my name to this specification.

GALEN H. CLEVINGER.
